Inventor:
Ralph P. Thompson

UNITED STATES PATENT OFFICE

RALPH P. THOMPSON, OF SOMERSET COUNTY, MARYLAND

FILING MACHINE

Application filed June 4, 1927. Serial No. 196,549.

My invention relates to filing machines for taking care of notes, papers or writings to be filed, and which are to be brought forth at a certain time. I therefore desire that it be called a time file for notes. It is especially adapted for taking care of notes in a bank, as by its manual operation the notes are brought forth at the right time to be cancelled.

The object of my invention is to provide suitable individual file holders for holding the notes, and to have a repository for these individual file holders in which they may be kept.

A further object is to so construct the file holders and the repository that any file holder may be partially withdrawn from its position of rest in the repository, but not fully withdrawn, for the purpose of inspecting its contents, adding thereto, or taking therefrom.

A further object is to have provision made for the absolute withdrawal from the repository of an individual file holder on occasion, with its contents undisturbed, for the purpose of using the files elsewhere than at the repository.

I accomplish these objects by a construction of the file holders and their repository as indicated by the following description and drawings herewith.

Figs. 1, 2, 3 and 4 represent different views of the individual file holder.

Fig. 5 is a plan view of a note form, suitable for filing.

Figs. 6, 7, 8 and 9 are views of the repository showing details of construction, and various positions of the file holders in which they are placed relative to the repository.

The file holder is made of pressed metal or other suitable material. Fig. 1 is a plan view opposite the surface whereon the filed notes repose. Fig. 2 is a side view showing the relative height of the sides. Fig. 3 is a plan view, showing at 4 an upwardly projecting finger. Fig. 4 is a sectional view on line 4-4 Fig. 3. The dotted lines represent the positions taken by the filed notes, and at 4 is shown the upwardly projecting finger.

Fig. 5 is a plan view of a note form 19, suitable for filing, and at one end a perforation, 4' will be noticed that fits properly over the

upwardly projecting finger 4, to hold the note from endwise play, while the sides of the file holder prevent its movement sideways.

In each view of the file holder a bar 3 will be noticed to pass through an extension of the sides and to project slightly at each end. These extensions of bar 3 control the relative positions that the file holder may bear to the repository.

A side elevation of the upper portion of the repository is shown at Fig. 6, with a portion of the side wall 5 broken out. The partition walls 6, which separate the file holders in the repository are shown in section, and it will be noticed that the file holder 7 is resting upon one of these partition walls, in an inclined position. When in this position its contents may be inspected, added to, or as sorted in any way.

The reaction from the pressure of the file holder where it rests upon the partition wall at 6, is taken up as shown in Fig. 8, where one end of bar 3 is shown bearing on the under side of disk 9 at 16, while the other end is shown bearing on the under side of the inwardly projecting side wall of the repository at 8. The file holders shown in Figs. 6, 7 and 8 are all in the same position relative to the repository.

Fig. 7 is a plan view of the repository with a portion of the top broken out to show the walls below in section. The disk 9 which forms part of the top to the repository, has a section of its rim cut away to form a gateway as shown at 10. Through this gateway only, is it possible to insert a file holder in the repository, or to fully remove one.

Fig. 9 shows a file holder, 7 at the left, in the act of withdrawal from the repository. One end of bar 3 has passed upward through gateway 10. As soon as bar 3 has cleared disk 9 the file holder swings free of the inwardly projecting side wall of the repository and thus becomes entirely detached.

The method of inserting a file holder in the repository requires but a reversal of this movement.

Fig. 8 shows a cross section on line 8-8 Fig. 7.

Fig. 9 is the same as Fig. 8, except at the 100

right the file holder 7 is shown within the repository in full rest position, while at the left the file holder is in act of withdrawal as previously described.

- 5 The file holders when at full-rest position within the repository, occupy contiguous positions which extend in an endless path. With the machine in practical operation each position would be occupied by a file holder, but 70
10 in the drawings all have been omitted except those necessary to show the various positions they take relative to the repository, in the belief that the drawings thus simplified will be easier read.
- 15 At Fig. 7 the file holder positions are shown at 11, 11 etc., wherein the lateral dimension of the compartment is sufficient to permit the bar 3 to pass freely up and down. The spaces marked 12, 12 etc., show a narrower opening 80
20 which is at the top and will not permit the file holder to be fully withdrawn.

The disk 9, Figs. 7, 8 and 9, forms a part of the top of the repository. This disk 9 revolves upon a stud 13 which is rigidly mounted to project from the stationary part of the repository at 14. Upon the upper end of stud 13 a ratchet wheel 15 is rigidly mounted thereby causing it to be retained in a fixed relation to the repository proper. A pawl 16 is mounted upon the disk 9, Fig. 7, and engages with the ratchet wheel 15. The ratchet wheel has notches in its rim to correspond in number to the number of file holder positions in the repository, and when the pawl 16 engages 85
35 with a notch of the ratchet wheel, the gateway 10 of the disk 9 registers with one of the file holder positions in the repository.

The knob 18 is used to manually operate the disk 9. In practical use the disk is advanced one notch of the ratchet wheel daily. As the file holders may be fully withdrawn 100
40 only when gateway 10 coincides with a file holder position, it follows that they are withdrawn in consecutive order as the gateway 10 is advanced daily from one position to the next.

The practical utility of my invention may be illustrated by supposing its use in a bank for taking care of notes and bringing them 105
50 forth on their due dates. Each file holder position of the repository would be occupied with a file holder for containing notes. As the gateway 10 is advanced one space each day it constitutes the time element from which 110
55 calculations can be made as to the proper file holders in which to file the notes to have them brought forth on their due dates. The notes falling due the first day of operation of the machine would naturally be contained in the file holder which at the moment may be withdrawn through gateway 10. The notes falling 115
60 due the day following will be contained in the file holder released by the next daily operation of disk 9, and so continuing, the notes falling due each day will be brought 120
65

forth in succession as gateway 10 is advanced day by day. As the notes come due the file holder containing them is released to be taken to the bank counter where the notes are cancelled. As each file holder is taken from the 70
repository an empty one is inserted in its place, to so remain to receive the filed notes until gateway 10 again comes into position for its release. The cycle of operations is 75 continuous.

Normally the file holders repose in their rest positions as shown at the right of Fig. 9. When a note is to be filed the file holder is partially withdrawn and rests in the position as shown at 7 Fig. 6. After the note is filed the 80
85 holder is dropped back to rest position as at the right of Fig. 9.

Having described my invention I desire to secure the following claims:

1. In a filing machine, a repository to support a series of removable file holders in contiguous positions extending in an endless path, a movable member supported by said repository, an extension on said movable member, said extension overlapping the endless path of the said file holder positions and thereby preventing the full removal of said file holders from said repository, and a gateway in the said extension of said movable member to give clearance for the full removal 90
95 of said file holders from said repository, and mechanical means for operating said movable member.

2. In a filing machine, a manually operated mechanism for timing the release of file holders, a series of file holders supported in contiguous positions extending in an endless path in a repository, an overlapping portion on said repository, an overlapping portion on said manually operated mechanism engaging the said file holders at their greatest lateral dimension to prevent their removal from the said repository, a gateway in the overlapping portion of said manually operated mechanism to release said file holders for their full withdrawal from said repository, and means for applying motion to said manually operated mechanism to cause it to advance from one release position to the next.
